(57) **CLAIM**

The ornamental design for a toothbrush head, as shown and described.

DESCRIPTION

FIG. 1 is a perspective view of our toothbrush head as seen from the top, front and right sides.

FIG. 2 is a left side view of our toothbrush head.

FIG. 3 is a front view of our toothbrush head.

FIG. 4 is a right side view of our toothbrush head.

FIG. 5 is a rear view of our toothbrush head.

FIG. 6 is a top view of our toothbrush head; and,

FIG. 7 is a bottom view of our toothbrush head.

The broken line showing of a handle and the rear of the brush head are included for the purpose of illustrating environmental structure and portions of the article that form no part of the claimed design.
